RECIPROCATING BRUSH DEVICE FOR
CLEANING SOLES OF SHOES

Clarence R. Aben, River Rouge, Mich.

Application December 16, 1944, Serial No. 568,478

2 Claims. (Cl. 15—37)

1

My invention relates to a new and useful improvement in a shoe cleaning mechanism adapted for use as a mechanically operated mat whereby the shoes of a person standing on the proper location of the mechanism will be automatically brushed and cleaned. The invention is intended for mounting at door entrances to private homes and public buildings such as department stores, theatres and the like. A suitable grating is provided and when a person steps upon the grate, which would be necessary in order to enter the building, the mechanism would be set into operation and brushes would be operated to brush particularly the soles and the sides of a person's shoes so that mud, slush and the like would be automatically removed before a person entered the building.

It is an object of the present invention to provide in a mechanism of this type reciprocating brushes which are reciprocated when the person is standing on the grating provided.

Another object of the invention is the provision of a mechanism embodying a grating and a plurality of reciprocating brushes so arranged and constructed that when a person steps upon the grating, the grating will move downwardly to establish a contact to close a circuit to the operating mechanism and the brushes will move upwardly between the spaces in the grates and when the person has stepped off of the grates, the grates will automatically rise to their normal positions and the brushes will automatically then lower to their normal positions.

It is another object of the present invention to provide in a mechanism of this class a plurality of brushes extending parallel to each other and arranged in two sets and provided with mechanism for reciprocating each set but in opposite direction to the other set.

It is another object of the present invention to provide a structure of this class which will be simple in operation, economical of manufacture, durable, compact and highly efficient in use.

Other objects will appear hereinafter.

It is recognized that various changes and modifications may be made in the detail of structure illustrated without departing from the invention itself and it is intended that such variations and modifications shall be encompassed within the scope of the claims which form a part of this specification.

Forming a part of this specification are drawings in which,

Fig. 1 is a top plan view of the invention;

2

Fig. 2 is a sectional view taken on line 2—2 of Fig. 1;

Fig. 3 is a fragmentary, sectional view taken on line 3—3 of Fig. 2;

Fig. 4 is a bottom plan view taken on line 4—4 of Fig. 2;

Fig. 5 is a view taken on line 5—5 of Fig. 3;

Fig. 6 is a fragmentary, enlarged view of the make and break mechanism used in the invention;

Fig. 7 is a fragmentary, sectional view taken on line 7—7 of Fig. 4 and rotated to upright position;

Fig. 8 is a fragmentary, sectional view taken on line 8—8 of Fig. 4 and rotated to upright position;

Fig. 9 is a sectional view taken on line 9—9 of Fig. 1;

Fig. 10 is a fragmentary sectional view taken on line 10—10 of Fig. 1;

Fig. 11 is a sectional view taken on line 11—11 of Fig. 4 and rotated to upright position.

Fig. 12 is a sectional view of one of the brushes taken on line 12—12 of Fig. 1.

Fig. 13 is a sectional view taken on line 13—13 of Fig. 12.

As shown in the drawings, I provide a box-like container having a bottom 17, end walls 18 and 19, side walls 20 and 21, a stationary top wall 22 and swingably mounted on this stationary wall 22 is a frame 23 having flanges 24 and 25 which rest on the side walls 20 and 21 and the end edge of frame 23 rests on the end wall 18 to maintain the frame in horizontal alignment with the wall 22, the upper faces of the wall 22 and the frame 23 lying flush with each other. Projecting downwardly from the frame 23 are side flanges 27 and 28 and end flanges 29 and 30, the end flange 30 being cut away as at 31 (see Fig. 4). Each of the side flanges is similarly constructed, so that a description of one will suffice for both.

As shown in Fig. 3, the side flange 27 is provided with a pair of openings 32 and 33. Similar openings are formed in the side flange 28, the purpose of which will appear later. Pivottally mounted on each of these side flanges, as at 34, is a link 35, one end of which is pivotally connected to the arm 36 and the other end of which is pivotally connected to the arm 37. Mounted on the flange 27 are bearings 38 and 39. Similar bearings 40 and 41 are mounted on the flange 28 and rotatably mounted in the bearings 39 and 41 is a shaft 42. A similar shaft 43 is mounted in the bearings 38 and 40. A cam plate 44 is

fixedly attached at 45 to the shaft 42. A cam

Fig. 1 is a top plan view of the invention;

plate 46 is fixedly attached at 47 to the shaft 43. The link arm 37 is pivotally connected as at 48 to the plate 44 and the link arm 36 is pivotally connected as at 49 to the plate 46. Each of these plates carries a roller 50 which projects through the opening 33 or the opening 32, as the case may be.

A floating supporting frame is provided in the mechanism consisting of a cross head embodying the bars 51 and 52 (see Fig. 4) connected together at their ends by the plates 53 and 54 to provide a box-like structure open at two of its sides (see Fig. 1 and Fig. 8). A similar cross head is provided at the opposite end consisting of the bars 54 and 55 connected at their opposite ends by the end plates 56 and 57 to provide a rectangular frame or box-like structure open at two of its sides (see Fig. 11). Connecting these cross heads are guide rails 58 and 59 (see Fig. 1 and Fig. 11). Each of these guide rails is slidably projected through a tubular member 60 or 61 which is mounted between the bars 51 and 52 or the bars 54 and 55 (see Fig. 8). A set screw 62 is threaded through one of the bars into the member 60 or 61 and a similar set screw 63 is threaded through the other bar into the member 60 or 61. The plates 44 and 46 are pivotally connected as at 64 and 65 to the cross heads (see Fig. 4).

A brush supporting frame is slidably mounted on the guide rails 58 and 59. This brush supporting frame consists of a pair of sections of channel shaped brush retainers 66 in each of which is mounted a brush 67, the mounting being in the nature of a press fit so that the individual brushes may be removed and replaced when necessary. In each of these channels 66, there is a spring 68 at opposite ends which serves to engage the brush back 69 and prevent undue removal of the brush from its retainer 66. As clearly shown in Fig. 4, I provide a plurality of cross bars 70, 71, 72 and 73. Each of these cross bars is provided with a pair of knuckles 74 through which the guide rods 58 and 59 slidably project. Connected to the cross bars 70 and 71 are the brush retainers 66, every other brush retainer being connected to these bars. Connected to the bars 72 and 73 are the other brush retainers. Connected to the bar 72 is a pitman 76 and a pitman 77 is connected to the bar 71.

For operating the mechanism, I provide a motor 78 driving a pulley wheel 79 connected by the belt 80 to the pulley 81 fixedly mounted on the shaft 82. Fixedly mounted on the shaft 82 is a gear 83 which meshes with and serves to drive the pinion 84 which is fixedly mounted on the shaft 85. This shaft, as shown in Fig. 2, Fig. 5, Fig. 10 and Fig. 11, is provided with a pair of cranks 86 and 87; one of these is connected to one end of the pitman 76 and the other to one end of the pitman 77.

The construction is such that when the motor is operated, the set of brushes connected to the bars 72 and 73 will be reciprocated in one direction and the set connected to the bars 71 and 70 will be reciprocated in the other direction.

I provide a grating 88 which is adapted to rest upon the rollers 50, the spaces 89 between the grate bars 90 registering with the brushes which are positioned below. The construction is such that when a person steps upon the grating, downward pressure will be exerted upon the rollers 50 causing the plates 44 and 46 on one side of the supporting frame and the similar plates on the other side of the supporting frame to rock

downwardly on the shafts 42 and 43 as pivots. As this downward rocking is effected, the points 64 and 65 on both sides are elevated so that the supporting frame embodying the cross heads is raised, thus carrying the brush retainers upwardly sufficiently to project the bristles on the brushes above the upper surface of the grate bars. This would, of course, elevate the supporting structure of the motor and the gearing, this supporting structure consisting of the bars 92 and 93 and the spacing and connecting members 94, 95 and 96. There is thus sufficient weight so that when the person steps off of the grating, the plates 44 and 46 and the corresponding plates on the opposite side of the structure will rock downwardly to their normal position so that the bristle of the brushes is normally positioned below the upper surface of the grating. This makes it possible to have a grating and brush arrangement so that a minimum number of both parts is required in order to effect the proper operation. This is an advantage particularly in public places as it is not necessary for the grating to be lowered to as great an extent as it would be were the brushes to remain stationary instead of also moving upwardly as the grating moves downwardly.

As previously mentioned, the flange 29 is cut away as at 31 and the rods 58 and 59 are projected through the flange at the cut away portion with sufficient clearance to permit these rods to move upwardly when the plates 44 and 46 are rocked. The rods at the opposite end project through the flange 30 and this flange is provided with a slot 97 (see Fig. 10) of sufficient clearance so that the rods may move relatively to the flange when the up and down movement of the brush supporting frame is accomplished. Consequently, the assembled structure embodying the cross heads and the guide rods, together with the sets of brushes having their cross bars connected therewith, as well as the motor mounting, is mounted in a floating arrangement so that this up and down movement of all of these parts may be effected.

A switch 101 is provided for controlling the circuit to the motor, this switch being interposed in a suitable circuit and operated by the button or plunger 102. When a person steps on the grating, forcing the plates 44 and 46 to rock so as to elevate the structure, the button 102 will be brought into engagement with the plate 103 (see Fig. 6) mounted on the guide rods 104 and 105 and normally pressed by the springs 106 into engagement with the switch button 102. As the upward movement is effected, the switch will be closed and the motor operated to reciprocate the two sets of brushes so long as a person is standing on the grating.

With a construction of this type, it is apparent that a person's shoes are automatically and very easily and quickly brushed as he passes over the grating, thus preventing the carrying of slush, mud and other undesirable material into the interior of a building. Experience has shown that a device of this type is particularly desirable where a person entering the building is to travel over carpets or rugs, a tile floor or a carefully attended floor.

What I claim as new is:

1. In a shoe cleaning machine of the class described, a supporting structure having an open top; a swingably mounted cover for said top, having an opening formed therein; a plurality of cams rockably mounted on said cover and posi-

tioned within said supporting structure; a supporting frame below said cover and pivotally connected to one end of said cam plates and adapted for upward and downward movement in response to the rocking of said cam plates; guide rods on said supporting frame; a plurality of brush members slideably mounted on said guide rods; a grating positioned in said opening and forming a closure therefore and comprising a plurality of spaced apart bars extending parallel to said rods, each of said brush members being in alignment with one of the spaces between said bars; a roller on the opposite ends of said cams for engaging and supporting said grating, said grating being moveable downwardly upon a predetermined weight being placed thereon, the connection of said cam plates with said supporting frame being such that upon downward movement of said grating said supporting frame will be moved upwardly sufficient to project said brush members to extend above the upper surface of said grating; means for connecting said brushes into a pair of sets, alternate brushes being connected in one set and alternate brushes being connected in another set; a rotatable wheel; a pair of pitmans, each pitman connecting one of said sets eccentrically to said wheel; a motor for rotating said wheel; and a mounting for attaching said motor and said supporting frame and said wheel together for movement vertically in unison.

2. In a cleaning machine of the class described, a pair of shafts; a cam plate mounted on each of said shafts and rockable on the axis thereof; a supporting frame pivotally connected to one end of said cam plates and adapted for upward and downward movement in response to the rocking of said cam plates; guide rods on said supporting frame; a plurality of brushes mounted on said guide rods and reciprocable thereon

longitudinally thereof; a grating embodying a plurality of spaced apart bars, the spaces between said bars extending parallel to said rods, and each of said brushes being in alignment with a space between said bars; an engagement member on the opposite end of each of said cam plates for engaging and supporting said grating, said grating being movable downwardly a predetermined distance upon a predetermined weight being placed thereon, the connection of said cam plates with said supporting frame being such that upon downward movement of said grating said supporting frame will be moved upwardly sufficient to project said brushes above the upper surface of said grating; means for connecting said brushes into a pair of relatively moveable sets, alternate brushes being connected in one set and alternate brushes being connected in another set; a rotatable wheel; a pair of pitmans each pitman connecting one set of said brushes eccentrically to said wheel; and a motor for rotating said wheel, the connection of said pitmans to said wheel being such that upon rotation of said wheel said sets of brushes will be reciprocated simultaneously in opposite directions; and connecting members for connecting said motor and said wheel to said supporting frame for movement in unison therewith.

CLARENCE R. ABEN.
